UNITED STATES PATENT OFFICE.

ROBERT W. JONES, OF WILKES-BARRE, PENNSYLVANIA.

RETAINING MEANS.

1,394,177.

Specification of Letters Patent.

Patented Oct. 18, 1921.

Original application filed December 18, 1917, Serial No. 207,807. Divided and this application filed August 5, 1918. Serial No. 248,284.

To all whom it may concern:

Be it known that I, ROBERT W. JONES, a citizen of the United States, residing at Wilkes-Barre, Luzerne county, Pennsylvania, have invented new and useful Improvements in Retaining Means, of which the following is a specification.

This invention relates more particularly to that class of retainers designed to prevent accidental disengagement of rotatable devices from their driving shafts, and constitutes a divisional part of my original application, filed December 18, 1917, Serial No. 207,807, although its use is not restricted to this class 15 of work, as it may be applied to stationary supporting members to retain rotatable devices thereon, and is useful in many other ways.

From the variety of uses to which the invention may be put, I have chosen to illustrate its employment in connection with winding and rewinding machines for cinematographic films.

In this art, it has been customary to provide a winding machine having a suitably driven shaft or spindle adapted to support the empty reel or spool on which the film is to be wound, the hub of said reel or spool being preferably recessed to fit over or accommodate a spline fast on the shaft.

A filled reel or spool may be suitably supported on a second spindle or shaft arranged parallel with the driven spindle or shaft, and the end of the film connected to the hub 35 of the empty spool.

As the driven spindle turns, it rotates the empty spool to unwind the film from the filled reel and wind it on the empty reel.

This operation is performed innumerable 40 times during the life of a film, and the speed with which such operation can be completed, without damaging the film, is important.

Obviously, since it is often desirable to rewind the films at the maximum speed of 45 which the driven spindle is capable, both the unwinding and rewinding spools or reels must rotate at a very high rate of speed, and at such speed tend to slip off the spindles.

As this accidental disconnection of the 50 spools from the spindles would result in great delay, to say nothing of the damage to which the film would be subjected, it has been customary to thread the outer ends of the spindles and apply nuts thereto, after the inser-

tion of the spindles through the hubs of the 55 spools, to prevent such disconnection.

While these nuts answer the purpose to a certain extent, they have the disadvantage that they require a little time to apply and remove, and often necessitate the use of a 60 tool in their removal, especially when set tightly against the inner end of the threads.

Obviously, the threads in the nuts must be matched with the threads on the spindles, before turning the nuts on the spindles, to 65 avoid cross-threading, which sometimes requires a little time and attention on the part of the operator.

Furthermore, and more important, the spindles are turned in opposite directions to 70 their usual direction of rotation, as when inspecting the film and in rewinding films after each projection on the screen.

Such reverse rotation often operates to turn the securing nuts off of the spindles to 75 permit the disengagement of the reels therefrom, due to the pressure of the reels against the inner faces of the nuts, when the reels are turned, or to vibration when the nuts are not set tightly.

My invention is designed to obviate all of 80 the foregoing disadvantages which film operators have submitted to for years.

Thus, one object is to provide a retainer which is more easily and quickly applied to 85 and removed from the spindles, at a minimum of labor and attention on the part of the operator, and wholly without the use of tools of any sort.

Another object is to provide a retainer 90 which will prevent the accidental disengagement of reels from their spindles, notwithstanding the direction of rotation of the spindles.

A further object is to provide a retainer 95 which will remain secured on the spindle against accidentally working loose from any cause.

Still another object is to provide a retainer so arranged that the outward thrust 100 of the reels thereagainst will result in causing the retainer to more securely grip the spindle.

To these and other ends, my invention includes the various novel features and combinations of parts, all of which will be more fully explained hereinafter and particularly set forth in the claims.

In the accompanying drawings, Figure 1 is a side view, partly in section, of one embodiment of my invention applied to the driving shaft of a film winding and rewinding machine;

Fig. 2 is a transverse cross-sectional view through the retainer and shaft, taken on line $\alpha-\alpha$ of Fig. 1, and

Fig. 3 is a detail view, showing the slot or way formed on the shaft.

Referring more particularly to Fig. 1 of the drawings, the standard film reel or spool comprises a hub 1 to the opposite ends of which are secured the circular sides 6. The hub is preferably recessed, as at 2, to fit over and accommodate a spline 7 formed adjacent a collar 8 on the projecting end 5^a of a driving shaft or spindle mounted to rotate in suitable bearings and driven in any convenient manner.

Rotation of the spindle or shaft 5^a turns the spool or reel to effect the coiling or winding of the film thereon.

The outer free end of the driving shaft or spindle projects beyond the outer side 6 of the reel and in the present embodiment of the invention, such outer free end is provided with a hook-shaped or bayonet slot 92 whereby to enable the retainer to lock itself upon the shaft, and prevent the accidental disengagement of the spool or reel and shaft.

The retainer, in the present instance, includes a hollow cylindrical drum or arresting member 87, closed at one end except for an aperture therethrough to permit its insertion over the outer grooved end of the shaft or spindle 5^a . The apertured end wall 87^a lies adjacent the outer end of the hub 1 of the spool or reel. One end of a coiled spring 93 inclosed within the barrel 87 presses the end wall 87^a against the hub of the spool to hold the latter against the collar 8 on the spindle and prevent lateral play of the spool which might develop to such an extent as to result in the disconnection of the hub 1 and its spline 7.

An apertured cap 88 having a threaded flange 88^a adapted to screw onto the open threaded end of the drum or arresting member 87, closes said open end, the cap constituting a means to connect the spool-arresting member 87 with the locking member, or key.

Such locking member or key, includes a head or finger piece 95, preferably knurled to facilitate its operation, secured to the outer end of a cylindrical barrel 89 chambered or provided with a socket at its inner end, as at 90, to fit over the free end of the spindle 5^a , and having a locking pin or bit 91 projecting into the chamber to enter and follow the bayonet slot or groove 92 formed in or on the spindle.

The cylindrical barrel of the key projects through the aperture in the cap or connect-

ing member 88, and carries an annular shoulder 94, the outer face of which bears against the inner face of the cap around the aperture thereto to prevent disengagement of the locking and arresting members. The outer end of the spring 93 contacts the inner face of the shoulder, the spring being of such length that it is normally under tension, when the retainer is assembled with the cap screwed onto the drum, to press the drum against the outer end of the hub 1 of the spool.

The open end of the groove or slot 92 extends to a point flush with the outer or free end of the spindle 5^a .

In applying the retainer to the spindle, the spool or reel is first placed on the spindle with the inner end of its hub against the collar 8, so that the recess 2 fits over the spline 7.

The operator then grasps the head 95 of the key of the retainer and brings the apertured end of the drum 87 toward the outer free end of the spindle to enter the latter in the drum, the spindle passing axially through the coiled spring 93.

The drum, or arrester is slid onto the spindle until its inner end contacts the outer end of the hub 1 of the spool or reel, after which continued pressure on the key compresses the spring 93 to yieldingly hold the arrester against the spool, and advances the chambered or socketed end of the key toward the spindle until the outer end of the latter enters the chamber or socket 90 of the key and abuts the locking pin or bit 91, whereupon the operator turns the key relatively to the spindle until the bit registers with the open end of the locking slot or groove 92. Further pressure of the key against the tension of spring 93 then causes the bit to travel along the slot or groove 92, the key being turned to cause the bit to follow the hook-shaped groove until it reaches the closed end of the slot which prevents further rotation of the key and spindle. Releasing the key at this point in the operation enables the spring 93 to snap the bit into its seat at the closed end of the groove to prevent accidental release of the retainer from the spindle.

It will be observed that the key barrel 89 and arrester 87 may turn and telescope freely relatively to each other, to permit the foregoing operation, in case the arrester should turn with the spool during the application of the retainer to the spindle either because of frictional contact or because of burs accidentally formed on the abutting faces of the hub 1 and the end 87^a of the arrester.

The retainer is disengaged from the spindle by pressing the key inwardly, to displace the bit 91 from its seat at the closed end of slot 92, and then turning the key in the re-

verse direction to cause the pin to retrace its path along the slot or groove until it reaches the branch leading to the open end of the slot, whereupon cessation of pressure on the 5 key will enable the spring 93 to jump the retainer off the spindle.

In practice, it is customary to start the spindle, as the retainer is being applied thereto, whereby to register the open end of 10 the groove with the bit, instead of turning the key to register the bit with the groove, and in this way, taking advantage of the rotation of the spindle to cause the bit to enter and follow the groove. Likewise, in removing 15 the retainer, the key is pressed inwardly to dislodge the bit from its seat, and the direction of rotation of the spindle reversed.

This enables the instant application and removal of the retainer.

20 The retainer will be effective irrespective of the direction of rotation of the spindle and also whether or not the arresting drum turns relatively to the key.

Also, the arresting drum 87 is of such 25 length that it enables the retainer to be used in connection with reels or spools of varying widths, the only difference being a variation in the degree of compression to which the coiled spring 93 is subjected.

30 The continued pressure of the arrester 87 against the spool or other article prevents the latter from rattling, and wabbling during rotation, and thus obviates a further objectionable feature of the prior art.

35 Changes may be made in the form and arrangement of the several parts set forth without departing from the spirit and scope of my invention, which, it will be understood, includes the reversal of arrangement 40 of the various elements relatively to each other.

What I claim as new, is—

1. The combination with a suitable support having a hook-shaped slot or groove 45 formed in one end thereof; of a unitary retainer removably applicable to the support to releasably retain a rotatable member thereon, the retainer including a locking member having a bore adapted to fit over the 50 outer slotted end of the shaft; a bit carried by the locking member and projecting into the bore, the bit adapted to be entered in and removed from the hook-shaped slot; an aper- 55 tured arresting member adapted to remov- ably surround the outer end of the support, the inner end of the arresting member normally in contact with the rotatable member to hold the latter in place; the arresting member being chambered to inclose the inner 60 end of the locking member; means to connect the arresting and locking members against disengagement, and to permit relative rotary and telescopic movement there- 65 of; and a spring inclosed within the arrest- ing member and bearing against the locking member to retain the latter where adjusted.
2. The combination with a suitable support; of a unitary retainer applicable to and removable from the support to releasably retain a rotatable member thereon; the retainer including an apertured drum adapted to inclose the outer end of the support, and prevent disengagement of the rotatable member and support; a locking member arranged axially of, and projecting into the drum, the locking member connected to the drum against disengagement therefrom, and to permit free relative rotation throughout a full circle in either direction, the inner end of the locking member adapted to releasably engage the support to lock the drum against accidental disengagement; means to releasably maintain the locking member where adjusted; and a finger piece on the outer end of the locking member to facilitate manipulation.
3. The combination with a suitable support; of a unitary retainer applicable to and removable from the support to releasably retain a rotatable member thereon; the retainer including an apertured drum adapted to inclose the outer end of the support, and prevent disengagement of the rotatable member and support; a locking member projecting into the drum, the locking member connected to the drum against disengagement therefrom, and to permit free relative rotation throughout a full circle in either direction, the inner end of the locking member adapted to releasably engage the support to lock the drum against accidental disengagement; and means to releasably maintain the locking member where adjusted.
4. The combination with a spindle; of a self-contained retainer applicable to and removable from the spindle as a unit, to releasably retain a rotatable article thereon; the retainer including a chambered arresting member adapted to fit over the support with its inner end in the path of removal of the article; a locking member, whose inner end projects into the outer end of the arresting member, and adapted to releasably engage the spindle; a spring interposed between the arresting and locking members; a cap through which the locking member extends, the cap adapted to close the outer end of the arresting member; and means on the locking member to coact with the cap to prevent disengagement of the locking and arresting members and permit relative rotary and telescopic movement thereof.
5. The combination with a driving shaft, and a spool removably applied thereto and rotated thereby; the outer end of the driv- 125 ing shaft projecting beyond the spool; of a retainer to releasably hold the spool in place on the shaft, including a hollow ar-

rester having an apertured end to accommodate the outer end of the shaft; an apertured connector closing the opposite end of the arrester; a manually-operable key, the 5 barrel of which is journal in the connector to permit relative rotary and telescopic motion between the arrester and key; a shoulder on the barrel within the arrester, to contact with the connector and prevent disconnection 10 of the key and arrester; the inner end of the key having a socket to fit over the outer end of the shaft; releasable inter-engaging means between the key-socket and shaft; and a spring adapted to bear against 15 the apertured end of the arrester, and the shoulder on the key barrel, respectively.

6. The combination of a spindle; of a retainer for holding an article on said spindle, including an arresting member adapted 20 to fit over the spindle and contact the article; a locking key telescopically mounted in the arresting member, and having a socket to fit over the end of the spindle, and projecting beyond the arresting member for 25 manipulation; means to limit the movement of the key outward with relation to the arresting member; the spindle having a locking groove formed therein; a locking pin carried by the key, and projecting into the 30 socket, to enter the locking groove; and a spring inclosed by the arresting member, the spring operative to press the latter toward the article and to hold the locking pin in locking engagement.

35 7. The combination with a spindle on which articles may be removably mounted for rotation; of a self contained retainer removably applied to the spindle, to prevent accidental disengagement of the article there-

40 from, and including an arresting member adapted to fit over the spindle, with its inner end adjacent the article; a manually-operable locking key, the inner end of which

enters the outer end of the arresting member, and provided with a socket to fit over 45 the end of the spindle, and releasably engage the latter; a closure for the outer end of the arresting member, the locking key being journaled in the closure to permit relative rotary and telescopic adjustment of 50 the locking key and arresting member; means coacting with the closure to prevent disengagement of the key and the arresting member; and a spring operative to press 55 the arresting member toward the article on the spindle, and to hold the locking key in effective position on the spindle.

8. The combination with a shaft, and means removably applied thereto; the outer end of the shaft projecting beyond said removable means; of a retainer to releasably hold the removable means in place on the shaft, including a hollow arrester, having an apertured inner end, to accommodate the outer end of the shaft; an apertured connector to close the outer end of the arrester; a manually-operable key, the barrel of which is journaled in the connector to permit relative rotary and telescopic motion between the arrester and key; means on the barrel 60 of the key within the arrester to coact with the connector to prevent disconnection of the key and arrester; the inner end of the key having a socket to fit over the outer end of the shaft; releasable inter-engaging 65 means between the key-socket and shaft; and a spring adapted to press the key outwardly relatively to the arrester; the outer end of the key barrel projecting beyond the connector to enable manipulation of the key by 70 75 the operator.
